UNITED STATES PATENT OFFICE.

RUPERT GEORGE DAWSON, OF OVERDALE, DUNBLANE, SCOTLAND.

DESIGN FOR A GLASS BOTTLE.

50,297.

Specification for Design.

Patented Feb. 13, 1917.

Application filed November 11, 1915. Serial No. 60,985. Term of patent 3½ years.

To all whom it may concern:

Be it known that I, RUPERT GEORGE DAWSON, of 82 Great Clyde street, Glasgow, Scotland, a subject of the King of the United Kingdom of Great Britain and Ireland, residing at Overdale, Dunblane, Perthshire, Scotland, have invented a new, original, and ornamental Design for Glass Bottles, of which the following is a specification, reference being had to the accompanying drawings, forming part thereof.

Figure 1 is a side view of the bottle.

Fig. 2 is a sectional view of part of the bottle and taken on the line A, A, Fig. 1.

Claim:

The ornamental design for a glass bottle as shown.

RUPERT GEORGE DAWSON.

Witnesses:

JOHN SIMPSON,
ADAM HASTIE SYME.
